UNITED STATES PATENT OFFICE.

REME A. BEAUSEJOUR, OF NEW YORK, N. Y., ASSIGNOR TO STANDARD VARNISH WORKS, OF PORT RICHMOND, NEW YORK, A CORPORATION OF NEW YORK.

ARTICLE-HOLDER FOR LIQUID-COATING MACHINES.

1,237,860.

Specification of Letters Patent. Patented Aug. 21, 1917.

Application filed March 19, 1915. Serial No. 15,481.

To all whom it may concern:

Be it known that I, REME A. BEAUSEJOUR, a citizen of the United States, and resident of the borough of Richmond, in the city 5 and State of New York, have invented new and useful Improvements in Article-Holders for Liquid-Coating Machines, of which the following is a specification.

This invention relates to improvements in article holders for use in connection with liquid coating machines and has for its object to provide certain improvements in the construction, form and arrangement of the holder whereby the articles may be suspended in any desired angular position to produce the best results when the articles are being treated with the coating liquid.

A practical embodiment of my invention is represented in the accompanying drawings, in which—

Figure 1 represents a carrier, a portion of a horizontal arm upon which the carrier travels, and a holder in side elevation, a number of doors, broken away at the bottom, 25 being shown supported in position in the holder,

Fig. 2 represents a front view of the same, and

Fig. 3 represents a horizontal section taken 30 in the plane of the line A—A of Fig. 1.

The holder comprises a bar 1 to which is rigidly secured at right angles thereto, a series of bars 2 by means of angle irons 3, located in the corner at the crossing of the 35 bars and riveted to the bars.

The holder is pivotally secured to a carrier 4 by means of a bolt 5 vertically mounted between the bar 1 and a yoke 6 secured to the bar. The bolt extends upwardly through 40 the carrier and is held in position by a nut 7. The holder is free to be rotated upon the bolt 5 suspended from the carrier, while the carrier 4 is fitted to travel along the horizontal arm 8. The detail of this carrier and 45 the horizontal arm, form no part of this invention and will not be more particularly described.

The bars 2 are provided with horizontal series of holes 20 for receiving the removable cross bars 9, which are adapted to receive the upper ends 10 of the extensible

supporting hooks. The lower ends 12 of said hooks are arranged to engage strips 13 secured to the tops of the doors 14.

A pair of these hooks are required to suspend each door in position in the holder. The hooks in each pair are of different lengths, as shown in Figs. 1 and 2, the purpose of which being to hold the door in an angular position. The upper end 10 of each 55 hook is screw threaded, as shown at 15, and the lower end 12 is screw threaded as shown at 16. The threaded ends 15 and 16 have a right and left screw threaded engagement with a nut 17, the turning of which upon the 60 ends will give a slight vertical adjustment to the tilt of the door or article to be coated.

To provide for suspending doors or articles of various widths, the cross bars 9 may be placed in any of the holes 20 in the bars 70 2 to suit the required width.

It is obvious that slight changes may be resorted to in the form, construction and arrangement of the several parts without departing from the spirit and scope of my 75 invention; hence I do not wish to limit myself strictly to the structure herein set forth, but

What I claim is:

1. An article holder for liquid coating 80 machines comprising a frame, bars mounted therein, and means for suspending articles in the desired angular position from said bars, said means comprising a pair of hooks adapted to engage opposite sides of the ar- 85 ticle.

2. An article holder for liquid coating machines comprising a rotatable frame, bars mounted therein, and means for suspending articles in the desired angular position from 90 said bars, said means comprising a pair of hooks adapted to engage opposite sides of the article.

3. An article holder for liquid coating machines comprising a rotatable frame, bars 95 mounted therein, and means for suspending articles in the desired angular position from said bars, said means comprising a pair of extensible hooks adapted to engage opposite sides of the article.

4. An article holder for liquid coating machines comprising a rotatable frame, bars 100

mounted therein, and means for suspending articles in the desired angular position from said bars, said means comprising a pair of extensible hooks of different lengths adapted to engage opposite sides of the article.

6 In testimony, that I claim the foregoing as my invention, I have signed my name in

presence of two witnesses, this 12th day of March, 1915.

REME A. BEAUSEJOUR.
